United States Patent Office

Des. 231,902
Patented June 25, 1974

231,902

STRIP OF STAPLES

Robert E. Olson, 9014 Callaghan Road,
San Antonio, Tex. 78230

Filed May 18, 1972, Ser. No. 254,834

Term of patent 14 years

Int. Cl. D8—08

U.S. Cl. D8—266

The figure is a perspective view of a strip of staples. The broken line illustration of printed matter is merely representative of the type of indicia that may appear on the staples and does not form a part of the claimed design. The side opposite that shown is identical to the side that is shown. The underneath of the top of the staples is a flat surface.

I claim:

The ornamental design for a strip of staples, as shown and described.
